UNITED STATES PATENT OFFICE.

CLARENCE Z. HUBBELL, OF SPOKANE, WASHINGTON, ASSIGNOR, BY DIRECT AND MESNE ASSIGNMENTS, TO HULL CONSTRUCTION COMPANY, A CORPORATION OF WASHINGTON.

HULL CONSTRUCTION OF BOATS.

1,289,781.

Specification of Letters Patent.

Patented Dec. 31, 1918.

Application filed March 19, 1918. Serial No. 223,432.

To all whom it may concern:

Be it known that I, CLARENCE Z. HUBBELL, a citizen of the United States, residing at Spokane, in the county of Spokane and 5 State of Washington, have invented certain new and useful Improvements in Hull Construction of Boats, of which the following is a specification.

The present invention relates to improvements in the hull construction of boats, and 10 particularly to the construction of concrete boats, the object of the invention being the provision of simple and efficient means for forming the hull or shell of a vessel of concrete by utilizing movable formers at the exterior of the hull, and in connection with these formers employing means for withdrawing the formers or supports after the hull is completed, all as will be more fully 15 described and claimed hereinafter, and as shown in the accompanying drawings.

The drawings illustrate one complete example of the physical embodiment of the invention constructed according to the best 20 mode so far devised for the practical application of the principles of the invention. The invention described herein and shown in the drawings applies exclusively to the outer formation of the hull, both at the 25 sides and bottom, the forms, cores, or formers for retaining the plastic material at the inner side of the vessel being purposely omitted.

Figure 1 is a cross section of a construction dock according to this invention, showing the hull completed, the supports in place, and the hull ready to be floated from the dock.

Fig. 2 is an enlarged view of one of the 30 devices for withdrawing the exterior side forms from the side of the hull.

Fig. 3 is a perspective view, in section of 35 one of a number of buoyant supports or pontoons for supporting the hull at the bottom.

Fig. 4 is a view similar to Fig. 1, but showing the supports withdrawn and the hull afloat in the dock.

Fig. 5 is a small, sectional view showing 40 the vessel in the construction dock and ready to be floated therefrom.

In the preferred form of the invention as 45 illustrated in the drawings I have shown the dock as made up of concrete side walls 1, 1, and thereabove the superstructure 2, and the

roof 3 is of usual form for buildings of this type, and a traveling crane for construction work is illustrated at 4. The dock is so situated that it may be flooded with water up to the water line as illustrated 60 at W. L. in the drawings, and around the four sides of the rectangular walls is arranged a ledge 5 formed by thickening the side walls, and having the ledge project inwardly as shown. At the side of the dock 65 and communicating therewith is a lock chamber 6, of greater depth than the construction dock, and by means of the gates 6' (Fig. 5) the completed hull may be lowered to pass out of the lock chamber 6 70 to tidewater, as indicated in Fig. 5.

The vessel or hull is indicated at the letter V and its keel is designated K, and in Fig. 1 of the drawings it will be seen that a longitudinal, central partition 7 extends the full length of the dock and divides it, at its bottom into two compartments 8, 8, and within these compartments at each side of the center partition, are arranged a series of buoyant supports or 80 pontoons indicated as a whole by the number 9. The pontoons are preferably of metallic construction as shown and hollow and formed with a flat bottom 10 and outer inclined wall 11 at the end, while the upper 85 wall of the pontoons, in each case is fashioned to conform to the exterior of the bottom of the hull of the ship, the compound curve 12 being of sufficient length to extend from the keel outwardly to the vertical side 90 wall of the hull, and these pontoons form the core upon which the bottom of the vessel is laid. At the outer end of each pontoon an elevated portion is formed, and the inclined face 13 is adapted to fit up 95 under the ledge 5 of the dock as in Fig. 1 to retain the pontoons in stable position. The pontoons are buoyant, but may be filled with water in order to sink them, and withdraw their support from the hull after completion thereof, and while buoyant, are held by anchoring chains 14 attached to the bottom of the dock and to the bottom of the pontoons.

To hold the pontoons stable and take the 105 strain of the load as the hull is built up, a number of brace arms are employed to support the pontoons, and arranged in groups or series, of which the center series 15 are located in openings 16 in the central parti- 110

tion 7 and these brace arms are attached to the rock shaft 15' which extends lengthwise of the dock through a passage provided for it in the bottom of the partition 7. Links 17 connect the arms to prevent excessive outward swing when the shaft is rocked to swing the arms outwardly under the pontoons or cores to support the pontoons, and these brace arms support the two series of groups of pontoons at the inner edges. At their outer edges, the pontoons are supported by similar brace arms designated 18 and 19 on their respective rock shafts 20 and 21. The series of brace arms 18 and 19 are operated by means of the draw rods 22 and levers 23 in the recesses 24 of the side walls 1, and the central brace arms 15 may be operated by means located at the rear end of the dock (not shown).

20 The pontoons are shown in position in Fig. 1 to support the hull while it is being made, but after the hull is completed, the pontoons are removed or withdrawn, and to accomplish this withdrawal water may be poured or pumped into the pontoons through the valved inlet pipe 25 of the pontoon, and as the weight of the water increases and overcomes the buoyancy of the pontoon it is lowered from contact with the hull. The initial movement of the lowering operation of the pontoon is preferably started at one end of the pontoon, to facilitate the opening of the joint between the upper surface of the pontoon and the exterior surface of the bottom of the hull, and for this purpose a comparatively low partition 26 is attached to the interior bottom of the pontoon to form a compartment 27. Now when water is first pumped into the pontoon 40 through inlet pipe 25 it will be seen that the water will be confined in the compartment 27 and not be permitted to flow freely to cover the entire area of the bottom of the pontoon, the consequence being that the pontoon is tilted with its declination toward the central partition 7. The separation of the pontoon from the hull thus starts at the keel, and gradually continues to the outer side of the vessel as the pontoon becomes 50 heavier as it is filled with water.

After the pontoons are removed the hull is still supported by means of a sufficient number of hydraulic jacks 28, arranged in two rows one at each side of the central partition, and to accommodate these jacks, the pontoons are fashioned with wells 29 extending vertically therethrough. The hydraulic jacks may be furnished with water pressure through the pipe 30, or 30' located 55 at the outside of the dock and provided with suitable connections for operating the jacks, and of course the jacks are controlled from the outside.

60 The cores for the sides of the hull comprise laterally movable, upright plates 31, 32,

against which the sides of the hull are built up, and these plates are held in position by means of the pivoted links 33, 34 and the connecting bars 35. The links 33 are pivoted at their ends to the plates 31 and the connecting bar, and the links 34 are pivoted at their ends to the connecting bar and the side walls of the dock. When the plates are in operative position the pairs of links are horizontally aligned, as in Fig. 2, and when the plates are withdrawn the links assume the position of Fig. 4. The upright cores are actuated automatically and simultaneously with the movement of the pontoons through the instrumentality of a pivoted bar 35' having a bent end or hook 36. This bar extends down through an opening in the ledge 5 and the lower end of the bar with its hook projects through an opening in the face of the wall of the dock. A suitable number of these connecting bars and pivoted bars are spaced along the side walls of the dock, and the inclined faces of the pontoons are provided with recesses 37 having abrupt shoulders 38, 39, that contact with the hook 36. Thus when the pontoon is being lowered by the weight of the inflowing water, the shoulder 38 at the upper end of the recess will encounter the hook and as the pontoon descends it will pull on the pivoted bar and the connecting bar and links to laterally withdraw the plates or vertical cores from the side of the vessel or its hull. Instead of separating the upright cores from the hull bodily, the plates are gradually separated from the hull, and withdrawn with a movement similar to the initial movement of the pontoons, and to accomplish this movement the uppermost pivot 39 is connected directly to the ends of the links, while the lowermost pivot 40 is connected with the links and connecting rod by means of a slotted connection 41, permitting a lost motion at the lower end of the connecting rod, and this lost motion is decreased as the links approach the uppermost pivot 39 until it disappears. Thus, when the downward motion of the pontoon pulls on the hooked end 36 of the pivoted bar, the uppermost links pull the upper edge of the upright cores or plates before the lower edge is moved with the result that the separation of the core and hull takes place first at the upper edge of the core and gradually extends to the bottom of the upright core, in this manner providing a gentle separation and avoiding breaks or marring of the hull. After the initial movement, the plates or upright cores are bodily moved laterally from the hull leaving the hull free, but still supported by the ledge 5 of the dock. In order to provide for access to the inlet pipes of the pontoons, openings 42 are provided, vertically through the ledge, and these openings receive the inlet pipes of the pontoons.

The operation of the different parts of the invention will be readily understood. After the hull has been properly formed, the hydraulic jacks are first raised to the bottom 5 of the hull to receive the load, and then the brace arms under the pontoons are withdrawn, and the hollow pontoons flooded with water as described, so that they will sink to the bottom of the dock and simultaneously withdraw the vertical cores or plates leaving the hull supported on the center partition and the jacks. The dock is then flooded 10 and the hull is floated and then floated through the lock chamber 6 and subsequently 15 through the lock gates to tide water.

Claims:

1. A dry dock for use in building concrete boats having a series of confined buoyant and submersible supports shaped to conform 20 to the exterior bottom surface of the boat and perform the function of molding surfaces.
2. A dry dock for use in building concrete boats having a central vertical keel partition, and a series of confined, buoyant and submersible supports each side of the partition forming molding surfaces for the bottom of the boat.
3. A dry dock for use in building concrete 30 boats having a series of buoyant, submersible supports forming molding surfaces for the bottom of the boat, and upright surfaces for the sides of the boat movable in conjunction with the submerging motion of the 35 supports.
4. A dry dock for use in building concrete vessels having a central keel partition and a series of submersible pontoons at each side of the partition confined between the walls 40 and partition, and upright molding surfaces for the sides of the vessel movable in conjunction with the submerging motion of the pontoons.

Copies of this patent may be obtained for five cents each, by addressing the "Commissioner of Patents, Washington, D. C."

5. A dry dock for use in building concrete vessels having a series of buoyant, submersible supports forming molding surfaces for the bottom of the vessel, and means for causing a gradual separation of the pontoon from the vessel as the pontoon is submerged. 45

6. A dry dock for use in building concrete 50 boats having a series of submersible, buoyant supports for the bottom of the hull, and upright molding surfaces for the sides of the hull movable in conjunction with the submersible supports, and means for tilting 55 the molding surfaces and supports in their initial movement of withdrawal from the hull.

7. The combination in a buoyant support as described having a molding surface and 60 having a water inlet, and said support formed with a receiving chamber near one edge whereby the support is initially tilted before being submerged.

8. The combination in buoyant, submersible, molding surfaces for use in building concrete hulls, of a partition in the molding surfaces forming a receiving chamber for water whereby the molding surfaces are initially tilted as the water flows therein to 70 submerge the molding surfaces, upright molding surfaces for the sides of the hull, and means for tilting said upright molding surfaces preparatory to withdrawing them from the sides of the hull. 75

9. The combination in a dry dock for construction of concrete hulls, of a series of buoyant pontoons coacting as molding surfaces to support the bottom of the hull, pivoted brace arms for relieving the pontoons of the load of the concrete hull, and means for moving said arms to inoperative position. 80

In testimony whereof I affix my signature.

CLARENCE Z. HUBBELL.
